UNITED STATES PATENT OFFICE.

EARL V. HILL, OF CHICAGO, ILLINOIS.

VENTILATOR FOR CARS.

1,312,177.

Specification of Letters Patent. Patented Aug. 5, 1919.

Application filed January 7, 1916. Serial No. 70,803.

To all whom it may concern:

Be it known that I, EARL V. HILL, a citizen of the United States, residing at Chicago, county of Cook, and State of Illinois, 5 have invented certain new and useful Improvements in Ventilators for Cars, of which the following is a specification.

My invention relates more particularly to an intake ventilator adapted to be applied 10 to the vertical sash at the front of the car and above the roof thereof. Intake ventilators have heretofore been very little employed for the reason that the amount of air taken into the car through the ventilator 15 depends upon the speed of the car, by reason of which, if the ventilator be of sufficient size to admit the required amount of air when the car is stationary or moving at slow speed, it admits entirely too much air 20 when the car moves at high speed, unduly cooling the interior of the car. On the other hand, if the ventilator has a capacity adapted for fast movement of the car, it is practically useless for ventilation when 25 the car is moving slowly or is stationary. By my invention I have provided a ventilator which is not open to this objection, but automatically controls the entrance of air so that substantially the same amount is 30 enters the car at all times, which amount is independent of the speed at which the car is moving.

In the accompanying drawing I have shown, and in the following specification 35 described, the preferred form of my invention. It is to be understood, however, that the specific disclosure is for the purpose of exemplification only, and that the scope of the invention is defined in the following 40 claims in which I have endeavored to distinguish it from the prior art so far as known to me, without, however, relinquishing or abandoning any portion or feature thereof.

45 In the drawing, Figure 1 is a longitudinal section through a ventilator adapted to a car, and through so much of the car itself as is necessary to understand the application of my invention, and Fig. 2 is a fragmentary detail in plan.

The roof 3, sash 4, and top-deck 5 of the car, may be and are shown as of an ordinary construction, though my invention is applicable to cars of whatever character. The 55 ventilator comprises a tubular casing 6, which may be of rectangular or other de-

sired cross-section, and open at the front as at 7, and rear as at 8, a flange 9 being provided at the latter opening for securing the ventilator to the frame 10, by which it is attached to the sash 4. If desired, though this is not essential, the ventilator may be provided with a series of pivoted plates 11, of the usual type for closing the opening into the car, and diffusion plates 12, 13 at 60 the front and rear, respectively of the ventilator for diffusing the air to all parts thereof. At the front the ventilator is preferably provided with inclined slats or louvers 14, to prevent rain or snow from driving in. 70

The main feature of my invention consists in a means for maintaining the amount of air fed to the car substantially the same, notwithstanding the speed at which the car may be moving. For this purpose I have 75 provided two hinged plates 15, 16, which together are adapted to substantially close the passage through the ventilator. The plate 15 is pivoted at 17 and provided with a lug 18, which receives an adjusting rod 19, 80 adapted to be held by screw 20. The plate 16 is preferably pivoted on the same axis as the plate 15, but is suspended from the axis by arms 21, extending from opposite edges of said plate 16, and movable past the edges 85 of plate 15, so that plate 16 may freely swing about its axis. It will now be apparent that the current of air driven through the ventilator by the motion of the car will swing the plate 16 rearwardly a distance dependent upon the speed of the air. The course of the air is as indicated by the arrows A, B, over the upper edge of the plate 16 and under the lower edge of the plate 15, and consequently the farther plate 16 is displaced 95 from the vertical by the current of air, the smaller is the passage between the plates. The weight of the plate 16 is so determined, and the plate 15 so adjusted, that the proper amount of air will pass through the opening between the plates, notwithstanding the speed of the car upon which the ventilator is mounted. 100

I have found, however, that unless special provision is made to the contrary, the 105 plate 16 is inclined to swing backward and forward under the pressure of the air. In order to obviate this difficulty, I provide for the escape of the air coming in contact with said plate. For this purpose the lower 110 wall or floor of the ventilator, which is curved as at 22 to correspond to the curve

of movement of the lower edge of the plate 16, is pierced at 23 by a series of slots 24, the forward ends of which are narrow, and the rear ends relatively broad, thus providing escape for a quantity of air proportional to the amount entering the ventilator. Beneath the ventilator I have provided cross-strips 26, 27, which form with the bottom of the ventilator and the roof of 10 the car, a transverse passage open at its ends and communicating with said slots 24, thus furnishing an escape for the air coming against the plate 16, and thereby steady- 15 ing the latter and preventing it swinging to and fro.

I claim:

1. An intake ventilator for cars and the like, comprising a casing, a plate 16 suspended therein and movable under the pressure of air to restrict the passage through 20 the ventilator, one of the walls of the ventilator adjacent, a movable edge of the plate having perforations so positioned as to be uncovered by movement of the plate to permit the escape of air.
2. An intake ventilator for cars and the like, comprising a casing, a plate 16 pivotally mounted in the casing and free to move rearwardly therein under air pressure, the 25 bottom of the casing being curved to correspond to the plane of movement of the edge of said plate, there being openings in the curved portion of said bottom adapted to

provide exit for the air pressing against said plate.

3. An intake ventilator for cars and the like, comprising a casing, a plate 15 pivotally mounted in the casing and free to move rearwardly therein under air pressure, the bottom of the casing being curved to correspond to the plane of movement of the edge of said plate, there being wedge-shaped openings with enlarged rear ends adapted to permit the escape of air from the front of said plate.

4. An intake ventilator comprising a casing, a plate 15 pivoted and adjustable therein, a plate 16 pivotally suspended upon the same axis as the axis of the plate 15 in the ventilator and coöperating with said plate 50 15 to control the passage of air through the ventilator, such swinging plate being movable under air pressure to restrict the passage of air.

5. An intake ventilator for cars and the like, comprising a casing, an abutment in the upper portion of the casing partially cutting off the passage of air therethrough, a plate 16 suspended substantially below the abutment, a pair of arms 21 pivotally suspending said plate in the casing upon an axis adjacent the upper portion of the abutment, said plate being free to move under the pressure of air entering the casing to a position to restrict the passage of air.

EARL V. HILL.
